(57) **CLAIM**

The ornamental design for the display screen or portion thereof with animated graphical user interface, as shown and described.

DESCRIPTION

FIG. 1 is a front view of a display screen or portion thereof with animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof; and,

FIG. 7 is a front view of a seventh image thereof.

The broken line showing of the display screen or portion thereof forms no part of the claimed design. The appearance of the animated images transitions successively between the images shown in FIGS. 1-7. The process or period in which one image transitions to another forms no part of the claimed design.
